UNITED STATES PATENT OFFICE.

HOWARD S. EVANS, OF PITTSBURG, PENNSYLVANIA, ASSIGNOR TO MACBETH-EVANS
GLASS COMPANY, OF PITTSBURG, PENNSYLVANIA, A CORPORATION OF PENN-SYLVANIA.

DESIGN FOR A LAMP-SHADE.

40,554.

Specification for Design.

Patented Mar. 1, 1910.

Application filed December 24, 1909. Serial No. 534,902. Term of patent 7 years.

To all whom it may concern:

Be it known that I, HOWARD S. EVANS, a citizen of the United States, residing at Pittsburg, in the State of Pennsylvania, have invented a certain new, original, and ornamental Design for Glass Lamp-Shades, of which the following is a specification.

The accompanying drawing, forming part of this specification, is a side elevation showing my design.

I claim—

The ornamental design for a lamp shade as shown.

HOWARD S. EVANS.
